(57) **CLAIM**

The ornamental design for a wheel weight removal hook, as shown and described.

DESCRIPTION

FIG. 1 is a front perspective view of one embodiment of a wheel weight removal hook showing the new design; FIG. 2 is a top plan view of the view shown in FIG. 1.

FIG. 3 is a first side plan view of the view shown in FIG. 1; FIG. 4 is a rear side plan view of the view shown in FIG. 1; FIG. 5 is a second side plan view of the view shown in FIG. 1; and,

FIG. 6 is a bottom plan view of the view shown in FIG. 1. The broken lines showing a liquid dispenser is for the purposes of illustrating environment and forms no part of the claimed design.
